LIGHTING FIXTURE

George Arras, Chicago, Ill.

Application April 29, 1931. Serial No. 533,743

8 Claims. (Cl. 240—78)

This invention relates in general to an electric lighting fixture and has more particular reference to a fixture for excluding gases and for preventing condensation within the fixture parts.

5 A principal object of the invention is in the provision of a lighting fixture which is sealed against the admission or escape of gases or vapors which may be inflammable or dangerous, or may tend to condense, due to the heat of a 10 lamp within the fixture.

A further object of the invention is in the provision of a liquid seal for a lighting fixture, either at the joint of the globe or reflector, or at the mounting of the fixture support.

15 Another object of the invention is in the provision of a sealed lighting fixture to prevent the admission of dirt, thereby keeping the globe clean for a longer time and making frequent cleaning unnecessary.

20 Other objects will appear hereinafter, the accompanying drawing illustrating preferred embodiments of the invention.

In the drawing:

Figure 1 is a sectional view of a fixture constructed in accordance with the principles of this invention and

Figures 2 and 3 are sectional details showing modifications of the liquid seal.

In many places where electric lamps are used 30 it is found that the heat of the lamp will cause a movement of gas or vapor to and from an enclosing globe, due to the expansion and contraction caused by the lamp when it is hot and cold. In some cases the vapor may condense 35 and collect in the fixture parts, as at the bottom of an enclosing globe or reflector, which may be objectionable if not actually dangerous.

It is also found that this action may occur in the pipes or conduits leading to the fixture, and 40 to provide a seal fixture, it is necessary also to seal the passage from the supporting conduit pipe. The present invention proposes to overcome both of these objections by providing a sealing compound or liquid at the juncture of the 45 enclosing globe and at the socket support for the lamp itself.

In carrying out this invention, the fixture comprises a holder 5 having a threaded connection 50 at its top with a conduit 6 and having exterior fins 7 for heat radiation. At the bottom of the holder is an external flange 8 for attaching a reflector 9 thereto by screws 10 or any other suitable fastening means and within the flange is a circular rib 11 which projects downwardly pro-

viding a space between it and the flange for receiving a fixture bowl or globe 12.

The fixture globe 12 has an external threaded portion 13 at its upper edge adapted to engage with a correspondingly threaded portion on the inner side of the reflector flange 8 and at the inner end of the holder recess is a gasket 14. However, this threaded end gasket connection does not ordinarily produce a joint impervious to the passage of gases or vapors and the globe 12 is therefore provided with an inner flange 15 which extends inside of the rib 11 and below the lower extremity thereof forming a circular groove 16 for receiving a sealing liquid or compound 17 which extends well up about the rib 11 so that even if the fixture is not hung exactly vertical, the sealing liquid will always cover the lower edge of the rib 11.

Within the holder 5 are projections 20 for receiving socket fastening screws 21, and surrounding the wire admission opening of the holder is a depending rib 22. A lamp socket 23 is supported by the screws 21 and an electric lamp 24 is threaded into the socket in a well known manner with conductors 25 extending therefrom into the conduit 6.

Within the holder 5 are projections 20 for receiving socket fastening screws 21, and surrounding the wire admission opening of the holder is a depending rib 22. A lamp socket 23 is supported by the screws 21 and an electric lamp 24 is threaded into the socket in a well known manner with conductors 25 extending therefrom into the conduit 6.

In order to seal the opening into the conduit and to connect the conductors 25, a liquid sealing cup 26 is interposed between the socket 23 and the projections 20 which is held in place by the fastening screws 21 and this cup has an upward flange 27 which extends below the lower edge of the depending rib 22 so that a sealing liquid or compound 28 placed in the cup will extend upwardly above the lower edge of the rib 22 but will leave a space below the lower edge of the rib and the bottom of the cup for loosely stringing the conductors 25 through the sealing compound. The many turns of the screws 21 through the cup 26 will make a liquid tight joint but gaskets 28 may also be placed about the screws to provide an additional seal.

Instead of forming the globe and holder with a double interengaging rim construction, a structure as shown by Figure 2 may be employed comprising a holder 31 with a lower flange 32 threaded on the outside and a globe 33 with an offset upper rim 34 having a lower threaded rim portion 35, the two threaded rim portions 32 and 35 being joined by a correspondingly threaded metal rim 36 which engages gaskets 37 and 38 at the top and bottom respectively. The reduced rim portion 34 of the globe forms a recess between it and the depending rim portion 32 for containing a sealing 39.

110

A somewhat similar modification is shown in Figure 3, in which the holder 40 has a lower rim 8 and rib 11 similar to that shown in Figure 1 and the globe has a single reduced rib 34 as shown in Figure 2, the joint being closed by a metal rim 36 which abuts the gaskets 37 and 38 at the top and bottom respectively. In this construction the rib 11 extends into a groove containing a sealing liquid 39 for making a gas-tight joint. 10 In these modified forms the globe is made with a single rim or flange which is a somewhat simpler construction and not so easily broken.

With all of these constructions it is obvious that the only joints for the passage of vapor or gas are closed and sealed by a liquid or sealing compound which prevents the admission of an objectionable gas, vapor or dirt either from the interior of the room or through the wiring conduit and even though there may be considerable 20 expansion and contraction of the air within the fixture it will not be sufficient to break the liquid seal. Furthermore, if the fixture becomes too heated the fins of the holder will radiate the heat thereby preventing expansion within the fixture.

25 I claim:

1. A lighting fixture comprising a holder, a lamp supported therein, means for sealing the lamp terminals in the holder, a globe with a circular well at the top into which the lower edge 30 of the holder projects, and a sealing liquid in the well into which the holder projects.

2. In a vapor-proof lighting fixture, a holder having a circular depending rib, a globe therefore having a circular sealing liquid containing well at the top into which the rib extends.

3. In a vapor proof lighting fixture, a holder having a depending rim, means forming a liquid holding container into which the rim projects, a lamp supported within the holder having supply means extending below the rim and through 49 a sealing liquid in the container.

4. In a liquid seal vapor proof fixture, a holder having a depending rim, a globe having an up-

wardly extending liquid holding ring groove into which the rim projects, and the rim and groove having quick detachable connecting threads independent of the liquid seal between them when connected.

5. A lighting fixture comprising a holder, a lamp supported therein, a globe also supported by the holder and with it enclosing the lamp, separate means comprising a ring container with sealing liquid therein forming a liquid seal at the top and at the bottom of the holder to prevent the admission or discharge of gases to or from the interior of the fixture.

6. In a lighting fixture, a holder, a globe supported thereby, and a fluid sealing joint between the globe and holder comprising cooperating upright and depending ribs at the junctures of the globe and holder to form a liquid receiving groove in the lower part into which a rib from the other part extends, and sealing liquid in the groove of a depth to partially cover the depending rib.

7. In a lighting fixture, a holder, and a globe having cooperating rim portions to extend one within the other and threaded means for connecting the globe and holder independent of the liquid seal and providing a liquid receiving groove between the rim portions, and a sealing liquid in the groove between the rim portions to prevent the passage of gas or dirt therethrough.

8. In a lighting fixture, a supporting holder having a conductor opening, a lamp within the holder having conductors extending through the opening and a liquid seal for the opening comprising a rib surrounding the opening and depending into the holder, the conductors extending through the liquid below the rib, and a receptacle for sealing liquid to receive the rib therein but providing a space below the rib for admitting the conductors theretunder and a sealing liquid contained in the cup and extending above the lower edge of the depending rib thereby covering the conductors which extend theretunder.
